ATTORNEY

UNITED STATES PATENT OFFICE.

DAVID S. STIMSON, OF KITTERY, MAINE.

DESIGN FOR A FRAME FOR WINDOW-PULLEYS.

SPECIFICATION forming part of Design No. 30,855, dated May 23, 1899.

Application filed April 13, 1899. Serial No. 712,932. Term of patent 14 years.

To all whom it may concern:

Be it known that I, DAVID S. STIMSON, a citizen of the United States, residing at Kittery, in the county of York and State of Maine, have invented and produced a new and original Design for a Frame for Window-Pulleys, of which the following is a specification, reference being had to the accompanying drawings, forming part thereof.

Figure 1 shows a side view of my design for a frame for a window-pulley. Fig. 2 shows a front or face view, and Fig. 3 a rear view, of same.

As shown in the drawings, the leading and material feature of my design consists in a hollow cylinder truncated at its extremities 1 and 2, as shown in Fig. 1. On the exterior surface of said cylinder, intermediate between

the truncated portions, is a screw-thread 3. The extremity of the truncated portion 1 terminates in a flange 5, as shown in Figs. 1, 2, and 3. As shown more clearly in Figs. 2 and 3, the cylinder has an opening 10, two sides of which, 6 and 7, are parallel plane surfaces, and two sides, 8 and 9, are arcs of circles. 20 25

Having described my invention, what I claim as new, and desire to secure by Letters Patent, is—

The design for a frame for a window-pulley, as herein shown and described.

DAVID S. STIMSON.
